ARTICULATED TRACTOR

Henry G. Geer, Minneapolis, Minn., assignor to Erickson Corporation, Minneapolis, Minn., a corporation of Minnesota

Filed Oct. 16, 1964, Ser. No. 82,199

Term of patent 14 years

(Cl. D14—3)

FIG. 1 is a view in side elevation of an articulated tractor, showing a new design;

FIG. 2 is a view in side elevation opposite that of FIG. 1, some parts being broken away;

FIG. 3 is a view in top plan;

FIG. 4 is a view in end elevation as seen from the left of FIG. 1; and

FIG. 5 is a view in end elevation as seen from the right with respect to FIG. 1.

I claim:

The ornamental design for an articulated tractor, as shown.
